UNITED STATES PATENT OFFICE.

WALTER H. POPPE, OF MINNEAPOLIS, MINNESOTA.

SHOE-TOP FORMER.

1,288,984.

Specification of Letters Patent. Patented Dec. 24, 1918.

Application filed March 12, 1917. Serial No. 154,084.

To all whom it may concern:

Be it known that I, WALTER H. POPPE, a citizen of the United States, resident of Minneapolis, county of Hennepin, State of Minnesota, have invented certain new and useful Improvements in Shoe-Top Formers, of which the following is a specification.

The object of my invention is to provide a device for holding up the top of a lady's high boot or shoe and prevent it from dropping down and wrinkling and also to stretch the top preparatory to cleaning or polishing the boot.

A further object is to provide a former for holding the top of the boot properly stretched when it is placed in a display window.

A further object is to provide a simple, inexpensive device designed for use in connection with an ordinary boot or shoe tree, provision being made for mounting the former on the rear portion of the tree.

The invention consists generally in various constructions and combinations, all as hereinafter described and particularly pointed out in the claims.

In the accompanying drawings forming part of this specification,

Figure 1 is a view of a lady's boot with high top, with a portion of the upper and top broken away to illustrate my invention therein,

Fig. 2 is a detail view, looking down on the top of the former,

Fig. 3 is a detail sectional view, showing the manner of mounting the former on the tree of the shoe or boot.

In the drawing, 2 represents a lady's boot, having the well-known high top 3 provided with lacing edges 4 and eyelets 5. 6 is a tree fitting within the boot and having a recess 7 formed therein over the heel portion of the boot, whereon my improved former device is mounted. 8 represents a member having studs 9 thereon seated within recesses 10 in the side walls of the recess and projecting upwardly through the angle portion of the boot. 11 is a second member mounted to telescope with the member 8 and having a pin 12 therein that is slidable in slots 13 provided in the member 8. These members are thereby mounted to telescope or slide longitudinally, one upon the other. A lever 14 is pivoted at 15 to the lower end of the member 8 and its upper end has a pivotal connection at 16 with a link 17 that

is pivoted at 18 on the member 11. This lever is provided with a suitable finger grip 19. The rocking of the lever 14 on its pivot will move it toward or from the member 8 and this lever, with the link 17, forms a toggle connection between the two members, operating to raise the upper member when the toggle is straightened and allow them to telescope one upon the other when the toggle is straightened or when it is broken. An arm 19' is provided at the upper end of the member 11 and projects upwardly and rearwardly therefrom and has a curved plate 20 which bears on the rear of the shoe and preferably has pin points 21 for digging into the leather and gripping the top. A plate 22, preferably of spring material, is secured at one end to the member 11 and projects forwardly therefrom and is provided with a cross arm 23 having lugs 24 to enter the opposite eyelets in the lacing edges of the shoe. When, therefore, the member 11 is raised, the spring plate 22 will be put under tension to lift up on the boot leg with a yielding tension, which will straighten out the leather, canvas or cloth of which the leg is made and hold it smooth and taut, and positively prevent it from wrinkling or creasing while being cleaned or when placed in a display window, and also keep the top or leg from dropping down and getting out of shape when the boot is not worn. The engagement of the upper end of the arm 19' with the upper portion of the top will serve to press it outwardly and stretch the upper part of the leg between the point where the lugs enter the eyelets and where the arm 19 engages the top.

To release the device, the finger grip 19 is pulled forwardly until the toggle is broken, when the members may be telescoped and the lugs 24 be disengaged from the eyelets.

The device may be made in various sizes and in various ways the details of construction herein shown and described may be modified, the essential feature of the invention consisting in the means for straightening or stretching the boot leg for display, cleaning or other purposes.

I claim as my invention:

1. A shoe top former comprising a member having means for mounting it within a shoe and provided with a part for engaging the top of the leg at the front thereof,

- and a lever device for extending said member to stretch the leg.
2. A shoe top former comprising a member having means for mounting it within a shoe and a toggle lever operated part for engaging the top of the leg at the front and back thereof to straighten or stretch the leg.
3. A shoe former comprising upright, relatively movable members, one to be seated in the bottom of the shoe and the other having an arm for engaging the rear upper portion of the shoe leg, a spring plate mounted on said last named member and projecting forwardly therefrom and having laterally extending parts for entering the eyelets and a lever device for moving one member with respect to the other and thereby putting said spring plate under tension to stretch the leg of the shoe.
- 20 4. A shoe former comprising a member composed of sections slidable one upon the other, the lower section having a seat within the shoe, the upper section having a part to engage the shoe top and a lever device for separating said sections to stretch said top.
5. A shoe former comprising a member composed of sections slidable one upon the other, the lower section having a seat within the shoe, the upper section having a part to engage the rear of the shoe top and a part to engage the front thereof, and a toggle lever mechanism for raising the upper section to stretch the shoe top.
6. A shoe former comprising a tree fitting within the shoe and having a recess in the rear portion thereof, a member seated in said recess, a second member mounted for longitudinal movement thereon and provided with means for engaging the upper part of the shoe top and a lever device for raising said second member to stretch the shoe top.

In witness whereof, I have hereunto set my hand this 9th day of March 1917.

WALTER H. POPPE.
